(57) **CLAIM**

The ornamental design for a battery module, as shown and described.

DESCRIPTION

FIG. 1 is a front, top, right side, perspective view of a battery module;

FIG. 2 is a rear, bottom, left side perspective view of the battery module of FIG. 1;

FIG. 3 is a front view of the battery module of FIG. 1;

FIG. 4 is a right side view of the battery module of FIG. 1;

FIG. 5 is a left side of the battery module of FIG. 1;

FIG. 6 is a top view of the battery module of FIG. 1;

FIG. 7 is a bottom view of the battery module of FIG. 1; and,

FIG. 8 is a rear view of the battery module of FIG. 1.

In the drawings, the broken lines represent portions of the battery module that form no part of the claimed design.

1 Claim, 8 Drawing Sheets
